UNITED STATES PATENT OFFICE.

OSCAR HAMMERSTEIN, OF NEW YORK, N. Y.

CIGAR-BUNCH AND PROCESS OF MAKING SAME.

1,142,164.

Specification of Letters Patent.

Patented June 8, 1915.

Application filed March 3, 1913. Serial No. 751,728.

To all whom it may concern:

Be it known that I, OSCAR HAMMERSTEIN, a citizen of the United States, and resident of the borough of Manhattan, city, county, and State of New York, have invented certain new and useful Improvements in Cigar-Bunches and Processes of Making Same, of which the following is a specification.

My invention relates to cigar bunches and 10 the manufacture thereof and has for its object to produce a bunch in which the use of a binder is made unnecessary and in which the necessity for first stripping the leaf used in the construction thereof can also be 15 avoided.

A further object of my invention is to provide an efficient and easily carried out process for making such bunches.

My invention will be fully described hereinafter and the features of novelty will be pointed out in the appended claims.

Reference is to be had to the accompanying drawings in which—

Figure 1 is a plan view of a booking of 25 tobacco leaves showing steps in my improved process; Fig. 2 is a diagrammatic cross-section thereof on the line 2—2 of Fig. 1; Fig. 3 is an edge view of a group or plurality of leaves illustrating steps in 30 my process; Fig. 4 is an exterior view of one form of completed bunch; Fig. 5 is an enlarged cross-section thereof on the line 5—5 of Fig. 4; Fig. 6 is an exterior view of the bunch as shown in Fig. 4 after the wrapper 35 has been applied thereto to complete the cigar; Fig. 7 is a view similar to Fig. 1 showing a modification of my process. Fig. 8 is an exterior view of a cigar constructed according to this modification; Fig. 40 9 is a view similar to Fig. 1 of still another modification of my process and Fig. 10 is an exterior view of a cigar constructed according to this last modification.

In carrying out my improved process as 45 illustrated in Figs. 1 to 6 inclusive of the drawings I preferably first pile up or book any number of complete or unstripped tobacco leaves with the points preferably though not necessarily all facing in the same 50 direction and in which the stems have been previously made readily combustible in any suitable manner. After this piling up or

booking has been completed to the desired thickness, I preferably cut through the same, transversely intermediate of the ends 55 of said leaves or along proper lines to secure the desired length of bunch. The cuts in the form of my invention now being described extend along zig-zag or undulating lines as indicated at 15 and divide the leaves 60 into intermediate or body portions 16, tuck or end portions 17 and head or end portions 18 as shown best in Fig. 1 of the drawings. Any number of leaves necessary to form a bunch of the desired thickness, for 65 instance, two, three, four or more are now removed from the booking or pile and the tuck portions 17 thereof turned or folded back on the bodies 15 after which the head portions 18 of said leaves are similarly 70 turned or folded back on said bodies all as indicated in dotted lines in Fig. 1 and in full lines in Fig. 3. If desired the head portions 18 may be turned back first and the tuck portions 17 turned back last instead of as mentioned, it being immaterial 77 which of the portions 17 or 18 is manipulated first, or said head portions and tuck portions instead of being turned back may be otherwise placed upon the body portions. 80 In some cases the ends of these portions may overlap, although this is not essential. The said leaves with the various portions in said folded, turned back or other relation are now simply rolled up spirally or otherwise 85 manipulated in the usual manner as shown in Fig. 5 to form the bunch, which when constructed in this manner is of sufficient temporary compactness to hold its shape if desired without the use of a binder, 90 and in this condition is ready to be inclosed in the necessary wrapper for finishing the cigars.

As shown in Fig. 4 the zig-zag or undulating cuts 15 when the bunch has been 95 rolled or otherwise completed produce a number of tapering ends or scalloped portions at each end thereof, which may be brought together, or in other words provide the necessary yielding of the bunch at 100 each end to properly form the head and tuck when the wrapper is applied to complete the cigar, as illustrated in Fig. 6.

In the modification shown in Figs. 7 and

8 the cut near the broad ends of the leaves instead of being zig-zag or scalloped extends straight across said leaves as indicated at 15^a while the cut near the pointed ends 5 of said leaves may be the same as those shown in Fig. 1. When leaves cut in this manner are folded or otherwise combined and rolled or otherwise worked into a bunch only the head of the cigar will be pointed 10 after the wrapper has been applied, while the tuck thereof will be broad or straight and a cigar of what is commonly known as a panatela shape as illustrated in Fig. 8 is produced. In the modification shown 15 in Figs. 9 and 10 the leaves are cut straight across as indicated at 15^b in Fig. 9. When leaves cut in this manner are folded or otherwise combined and worked into a bunch both ends of the cigar will be approximately straight after the wrapper has 20 been applied and a cigar commonly known as a cheroot will be the result. It is to be understood that in both modifications, the tuck portions 17 and head portions 18 are 25 folded, turned back or otherwise placed upon the bodies 16 in the same manner as described with respect to Fig. 1 *et seq.*, the only difference between the various forms 30 of my invention being in the arrangement and form of cuts. By first arranging the leaves in bookings, then cutting, folding or combining and rolling the desired number into bunches as described absolutely all 35 scrap and waste of leaf is eliminated and the stems of all of the leaves extend longitudinally of the cigar and insure perfect combustion.

It is to be understood that it is not absolutely necessary to cut a large booking of 40 leaves before removing any therefrom and that the required number of leaves say two, three or four may first be taken from the pile or booking and then cut and the portions thereof then manipulated and described. In 45 addition to this in some cases the leaves may be stripped and then cut and used as indicated or one or more stripped leaves may be combined in any manner with one or more unstripped or complete leaves and cut, folded and rolled into a bunch in the manner 50 mentioned. Furthermore one or more complete or unstripped leaves cut and folded as shown may be wrapped about any other kind of filler to produce a bunch if this 55 should be found of advantage. It will also be obvious that in some instances the leaves need not be separated into individual body, tuck and head sections but may simply be perforated or scored along lines at which 60 the tuck and head portions are to be folded or turned back upon the body portion and formed into a bunch after which the ends of the bunch may be cut to provide the necessary drawing qualities.

While I have illustrated and described 65 the leaf as being cut or severed at two intermediate points and thus divided into three sections, the same may be cut or scored only once and divided into two sections or it may be cut or scored any additional number of 70 times and divided into any number of sections which may be combined as described to form the bunch, this operation depending on the length of leaf and the length of 75 bunch desired. In addition to this the leaf 80 may be folded and cut either along straight or undulating lines after having been folded. Also the section 18 may be placed at the end of the section 16 from which the section 17 is cut and the section 17 placed at the opposite end of said section 16 if this should be found of advantage.

With my improved process it is thus possible to construct cigar bunches in a simple and efficient manner from unstripped or 85 complete leaves and to do away with the use of a binder of any description if desired. In the present manner of making cigar bunches the filler is inclosed in a binder-leaf which must be wound spirally in the 90 direction in which the veins of the leaf extend to secure the best results, thus necessitating the making of right and left bunches, to be inclosed by right and left veined wrappers. With my improved process this 95 necessity is obviated, as complete leaves with the stems of the leaf lying in straight lines longitudinally of the bunch and requiring no special right or left working may be used.

100 Various changes in the specific forms shown and described may be made within the scope of the claims without departing from the spirit of my invention.

I claim:

1. The process of making cigar bunches which consists in placing a plurality of 105 filler leaves one upon the other and in registry with each other relatively to the central portion of each leaf, cutting said leaves transversely into end sections and intermediate sections, placing said end sections upon 110 said intermediate sections and then rolling up the combined sections to form the bunch.

2. The process of making cigar bunches 115 which consists in taking tobacco filler leaf piling it up with the leaves superimposed and in substantial registry with each other, cutting said filler leaf transversely of its length along undulating lines into end sections and an intermediate section, turning 120 said end sections back upon said intermediate section with the normal outer ends of said end sections extending toward each other and then rolling up the combined sections to form the bunch.

3. The process of making cigar bunches 125 which consists in placing a plurality of un-

stripped tobacco filler leaves one upon the other and in registry with each other, cutting said leaves transversely along zig-zag lines into end sections and intermediate sections, placing said end sections upon said intermediate sections and then rolling up the combined sections to form the bunch.

In testimony whereof I have hereunto set my hand in the presence of two subscribing witnesses.

OSCAR HAMMERSTEIN.
